UNITED STATES PATENT OFFICE.

HENRIETTE W. JONSON, OF PHILADELPHIA, PENNSYLVANIA, ASSIGNOR OF TWO-THIRDS TO ALICE E. FOX, OF PHILADELPHIA, PENNSYLVANIA.

MILK AND BREAD BOX.

1,223,178.

Specification of Letters Patent. Patented Apr. 17, 1917.

Application filed March 17, 1916. Serial No. 84,883.

To all whom it may concern:

Be it known that I, HENRIETTE W. JONSON, a subject of the Emperor of Germany, residing at Philadelphia, in the county of 5 Philadelphia and State of Pennsylvania, have invented certain new and useful Improvements in Milk and Bread Boxes; and I do hereby declare the following to be a full, clear, and exact description of the invention, such as will enable others skilled in the art to which it appertains to make and use the same.

This invention relates to that type of receptacles designed to be placed at the doors 15 of buildings for the collection of groceries, bottles of milk and the like, and the object of the invention is to provide a receptacle of this nature that will positively prevent the unauthorized withdrawal of articles that 20 have been deposited therein, and also one that will be of simple and durable construction and can be placed in operative position without necessitating alteration of the door or door frame.

25 Another object of the invention is to provide a device for carrying out the above objects and which includes a gate and a rotatable platform operatively connected with the gate, the said platform being designed to 30 have the deposited articles placed thereon and to be rotated during the rotation of the gate so as to move the articles thereon away from the gate.

Other objects will appear and be better 35 understood from that embodiment of my invention of which the following is a specification, reference being had to the accompanying drawings forming a part thereof, in which:

40 Figure 1 is a detail sectional view, taken through a door and door frame, and showing a receptacle in operative position, said receptacle being designed to receive bread and the like and shown in section.

45 Fig. 2 is a vertical section, taken on the line 2—2 of Fig. 1,

Fig. 3 is a sectional detail view, taken through one of the lower rear corners of the receptacle and showing the manner of securing the same to the door frame,

50 Fig. 4 is a view of another form of receptacle designed to receive bottles of milk,

Fig. 5 is a horizontal sectional view, taken through Fig. 4, and

Fig. 6 is a sectional detail view, taken 55 through the lower end of Fig. 4.

Referring to the drawings in detail, the letter A designates a door frame and B a door.

The receptacle shown in Figs. 1, 2 and 3 60 is designed particularly to receive loaves of bread, meat and such articles, and includes a bottom wall 1, front wall 2, opposite end walls 3, and a rear wall 4, the upper end of the receptacle being closed by means of a 65 door 5, which has hinged connection with the upper end of the rear wall 4. The said rear wall 4 is provided, at its lower end, with an opening 6, which is normally closed by means of the door B, and through which the 70 articles that have been placed within the receptacle can be removed.

The receptacle is designed to be placed on the door jamb, as shown in the drawings, and is secured in place by means of 75 elongated strips 7, formed of metal, each of which has one end secured to the side of the lower wall 1 and the rear wall 4, by means of the fastening elements 8, and has its opposite end extending rearwardly and beneath the lower edge of the door B, and is provided with openings which register with openings in the floor C, the said openings being designed to receive the fastening pins 9, so as to secure the receptacle in position. 80 As shown in Figs. 2 and 3 of the drawings the pins 9 lie in close proximity to the door B and serve as stops to limit the inward movement of the door should the latter be unauthorizedly opened. 90

Rotatably mounted within the receptacle is a shaft 10, the said shaft extending transversely of the receptacle and having its opposite ends journaled in the opposite end walls 3. Mounted on the shaft 10, and 95 adapted to rotate therewith, is a turnstile gate 11, the said gate being designed to prevent removal of the articles after the same have been placed within the receptacle. A ratchet wheel 12 is mounted on one end of 100 the shaft 10, and has its teeth interchangeably engaged by a pawl 13, the said pawl having one end pivoted to the adjacent end wall 3 of the receptacle by means of the pin 14. By virtue of the ratchet 12 and the 105 pawl 13 the shaft 10 and gate 11 can have rotation in one direction only.

The receptacle shown in Figs. 4, 5 and 6

is designed particularly to receive bottles of milk and as shown includes the bottom wall 15, side walls 16, and end walls 17, and top wall 18, and when the receptacle is in operative position, one of the side walls 16 is designed to lie adjacent the door B, and has an opening 19 formed therein and which is normally closed by means of the door B and through which articles deposited in the receptacle can be removed. One of the end walls 17 is provided with an opening 20 through which the articles are to be deposited within the receptacle.

In the said Figs. 4, 5, and 6, the shaft 10, and gate 11 instead of lying horizontally, as shown in Figs. 1, 2 and 3, are arranged vertically and the lower end of the shaft 10 extends into a recess formed in the under side of the bottom wall 15 and is provided with a sprocket wheel 21. A rotatable platform 22 is mounted within the receptacle and on the lower wall thereof and is operable beneath the lower end of the gate 11, and is carried by a vertical shaft 23, which has its lower end extended through the lower wall 15 and provided with a sprocket wheel 24. A sprocket chain 25 connects the wheels 21 and 24 on the shafts 10 and 23, so that when the gate 11 is rotated, rotation will be imparted to the platform 22.

As shown in Fig. 4, the upper end of the shaft 10 carries a ratchet wheel 26, having the teeth thereof interchangeably engaged by a pawl 27, which has pivotal connection with the upper end wall 18 of the receptacle, and which prevents rotation of the shaft and gate in one direction.

In inserting a bottle of milk in the receptacle, shown in Figs. 4, 5, and 6, the bottle is placed between those wings of the gate that lie adjacent the opening 20. The gate 11 is then rotated in the direction of the arrow, so as to move the bottle onto the platform 22. When the gate 11 is again rotated, so as to admit of another bottle being inserted into the receptacle, the platform 22 will be rotated and move the bottle that has been previously inserted away from the gate 11, so as to make room for other bottles. A stop 28 extends across the platform 22 and prevents the articles on the platform from passing the opening 19 during the rotation of the platform. While the receptacle, shown in Figs. 4, 5, and 6, is designed, es-

pecially for receiving bottles of milk, the same can be employed for receiving other articles.

Having thus described my invention what I claim as new, is:

1. The combination with a door and a door frame and a floor having an opening therein, of a receptacle located at the lower end of the door frame and adapted to receive articles and having an entrance opening in one wall thereof and an outlet opening in another wall thereof normally closed by the door, means within the receptacle for preventing removal of the articles through the inlet opening after the articles have been placed within the receptacle, a strip carried by the lower wall of the receptacle and extending beneath the lower end of the door and having a plurality of openings therein and adapted to be interchangeably registered with the opening in the floor, and a pin located in spaced relation to the door detachably received by the registering openings in the strip and the floor and having the upper end thereof projecting above the strip, for the purpose specified. 80

2. A receptacle having an inlet opening and an outlet opening in the walls thereof, a rotatable shaft journaled within the receptacle and located adjacent the outlet opening, a platform carried by the shaft 85 and operable across the outlet opening when the shaft is rotated, a second shaft journaled within the receptacle adjacent the inlet opening, means for preventing rotation of the second shaft in one direction, means 90 carried by the second shaft for engaging an article inserted through the inlet opening and for moving the article onto the platform when the second shaft is rotated, and to prevent the withdrawal of the article through 95 the inlet opening, a sprocket wheel carried by the first shaft, a sprocket wheel carried by the second shaft and operatively connected to the wheel on the first-mentioned shaft, whereby to effect rotation of the first 100 shaft when the second shaft is rotated, for the purpose specified.

In testimony whereof I affix my signature in presence of two witnesses.

HENRIETTE W. JONSON.
